BOWLING EQUIPMENT BAG

Julian A. Carreiro, Santa Susanna, Calif., assignor to Angelo N. Giordano and Joseph R. Raio, Canoga Park,
Calif., fractional part interest to each

Filed July 20, 1971, Ser. No. 164,488

Term of patent 14 years

Int. Cl. D3—02

U.S. Cl. D87—5 D

FIG. 1

FIG. 4

FIG. 2

FIG. 5

FIG. 3

FIG. 6

FIG. 1 is a side elevational view of a bowling equipment bag showing my new design;

FIG. 2 is a top plan view thereof;

FIG. 3 is a bottom plan view thereof;

FIG. 4 is a side elevational view thereof showing the side opposite to that shown in FIG. 1;

FIG. 5 is an end view thereof; and

FIG. 6 is an end view thereof showing the end opposite to that shown in FIG. 5.

I claim:

The ornamental design for a bowling equipment bag, substantially as shown.
